J. W. FARLEY

PLATE THIMBLE FOR PIPES

Filed April 4, 1927

Inventor
John W. Farley,

By *A. B. Willeson & Co*
Attorneys

UNITED STATES PATENT OFFICE.

JOHN W. FARLEY, OF CLEVELAND, OHIO.

PLATE THIMBLE FOR PIPES.

Application filed April 4, 1927. Serial No. 180,836.

The invention relates to plate assemblies, commonly known as plate thimbles, devices of this character being employed to extend around pipes and cover openings in floors, 5 walls, etc., provision being made whereby the pipes may move under expansion and contraction without injuring the thimbles.

It is the object of the invention to provide a generally improved and simplified 10 plate thimble construction, which may be easily and inexpensively manufactured, may be applied with ease and will be efficient and desirable in use.

With the foregoing in view, the invention 15 resides in the novel subject matter herein-after described and claimed, the description being supplemented by the accompanying drawings.

Fig. 1 is an outer side elevation of a plate 20 thimble constructed in accordance with this invention.

Fig. 2 is a vertical sectional view on line 2—2 of Fig. 1.

Fig. 3 is an inner side elevation.

Fig. 4 is a view similar to Fig. 3 but illustrating the plates swung apart for engagement with or disengagement from a pipe.

Fig. 5 is a transverse sectional view on line 5—5 of Fig. 3.

In the drawing above briefly described, 6 and 6^a denote two elongated metal plates having contacting longitudinal edges 7—7^a, which edges are formed with registering notches 8—8^a jointly providing a receiving 30 slot for a pipe P. The other longitudinal edges of the plates 6—6^a are formed with longitudinal flanges 9—9^a, said plates are provided at one end with end flanges 10—10^a, and these plates have similar flanges 40 11—11^a at their opposite end. All of the flanges project laterally in the same direction from the plates as will be clear from the several views.

A metal strip 12 is disposed in the angle between the plates 6—6^a and their end flanges 10—10^a, said strip extending across the line at which the edges 7—7^a contact with each other, being secured to the plate 6 by rivets 13, by spot welding, or in any other 50 desired manner, and being loosely pivoted to the plate 6^a. This pivotal connection comprises a slot 14 in the strip 12, and a rivet 15 passing through this slot and the plate 6^a, said slot permitting necessary shifting of

the plate 6^a toward or from the plate 6 when 55 applying or removing the device, as will be hereinafter more fully described.

The strip 12 is formed, in its outer edge, with an angular notch 16, which notch receives the inner end of the flange 10^a, when 60 plate 6^a is swung away from plate 6, as will be clear from Fig. 4. During this swinging, the inner corner 17 of plate 6^a, tends to crowd against the edge 7 of the plate 6 and would prevent relative opening of the two 65 plates, were it not for the loose pivotal connection 14—15. This connection, however, permits the corner 17 to move inwardly along the edge 17 and by allowing some lateral shifting of the plate 6^a with respect to 70 plate 6, permits relative swinging of the two plates without hindrance.

For connecting the ends of the plates which are provided with the flanges 11—11^a, I provide a channel-shaped metal strip 75 18 whose channel permanently receives the flange 11^a and is secured thereto by riveting, spot welding or the like. When the plates are in their closed positions, as seen in Figs. 1 and 3, the channel of the strip 18 also receives the flange 11 of the plate 6, but may be readily disengaged therefrom when the plates are to be swung into the relation shown in Fig. 4, when either applying or removing the device.

Screw holes 19 are formed in the outer corners of the plates 6—6^a and when said plates are secured to a floor, wall or the like, by screws or nails passing through these holes, they are held in assembled relation as 80 shown in Figs. 1 and 3.

For the purpose of sealing the slots 8—8^a, yet permitting shifting of the pipe P therein, I provide two relatively small plates 20—20^a which contact with the inner sides of the 95 plates 6—6^a and are located within the confines of the flanges 9, 9^a, 10, 10^a, 11 and 11^a. These smaller plates 20—20^a have notches 21—21^a formed in their inner edges to receive the pipe P, and preferably, these plates 100 are connected at one end in the manner shown, that is, by a strip 22 spot welded or otherwise secured to the plate 20^a as denoted at 23, but pivoted to the plate 20 as indicated at 24.

To slidably connect the two sets of plates, I prefer to secure metal strips 25—25^a to the inner sides of the plates 6—6^a, providing

them with offset edge portions which slidably engage the outer longitudinal edges of the plates 20—20^a.

Attention is now invited to Fig. 2. From this view, it will be seen that the ends of the plates 20—20^a, carrying the strip 22, are inwardly offset sufficiently from the plates 6—6^a, to clear the strip 12 and the fasteners 13—15, when said plates 20—20^a move toward said strip 12 to the maximum.

It will be seen from the foregoing that the invention is exceptionally simple and inexpensive and is of such construction as to permit rapid and easy manufacture. Moreover, it may be quickly and easily applied, or removed with equal ease. On account of these existing advantages for the details disclosed, they are by preference followed. However, within the scope of the invention as claimed, variations may be made.

I claim:

1. A device of the class described embodying relatively small plate means apertured to receive a pipe, two relatively large plates at one side of said plate means and notched to form a pipe-receiving slot, a strip contacting with the inner sides of said plates at one end of the latter and secured to one of these plates, a pivotal connection between the strip and the other of the relatively large plates, and means slidably connecting said plates with the plate means.

2. A device of the class described embodying two plates having contacting edges notched to form a pipe-receiving opening, the other edges of said plates having flanges projecting laterally in the same direction,

a strip in the angle between said plates and flanges and extending across the line at which the first named edges abut and rigidly secured to one of said plates, and a loose pivotal connection between said strip and the other plate, the outer edge of said strip being notched to receive the adjacent flange of said other plate when the two plates are swung apart about said pivotal connection.

3. A device of the class described embodying two plates having contacting edges notched to form a pipe-receiving opening, the other edges of said plates having flanges projecting laterally in the same direction, a pivotal connection between said plates at one end of the latter permitting separation of said contacting edges, and a channel-shaped strip receiving the flanges at the opposite end of the plates, said strip being secured to one of said flanges but being free of connection with the other.

4. A structure as specified in claim 2; together with a channel-shaped strip at the end of the plates remote from the first named strip and receiving the flanges thereat, said channel-shaped strip being secured to one of these flanges but being free of connection with the other.

5. A structure as specified in claim 1; the end of said plate means toward said strip being offset to clear the latter upon maximum movement of said plate means in one direction.

In testimony whereof I have hereunto affixed my signature.

JOHN W. FARLEY.
